UNIVERSAL PUNCH PRESS GUARD

Emil O. Gaul, Grand Haven, Mich., assignor to
 Grand Haven Stamped Products Company,
 Grand Haven, Mich., a corporation of Michigan

Application October 15, 1934, Serial No. 748,279

6 Claims. (Cl. 74—615)

The present invention relates to punch press guards, being directed toward the provision of a means for withdrawing the hands of an operator away from the punch press during the periods 5 that the press is performing its work, that is, as the punch is moved toward the die to operate upon a metal member to shape or form or pierce the same, which is work commonly done with punch presses.

10 The work is placed in the press usually by hand at a time when the punch is in an upper position. There is danger that the hands of the press operators may be injured due in many cases to negligence or carelessness in not removing the 15 hands after the work has been properly placed, so that the punch on coming down to the die may mutilate the hands or fingers of the operator.

With my invention I have provided a guard 20 which will serve to positively move the hands of the operator away from the die and away from the path of movement of the punch. The guard which I have provided is of substantially universal application, may be applied to many different types and characters of punch presses and 25 has a wide range of adjustment so as to be applicable to the same or different types of punch presses with different characters of work operated upon. It is also a feature of the present invention 30 that the distance the hands of the operator are withdrawn from the work may be controlled and adjusted. This may be desirable with different types and characters of work. In all cases it is 35 designed that the hands of the operator shall be fully and sufficiently withdrawn from the path of movement of the punch that injuries will be substantially eliminated.

Another great advantage of my invention, not 40 hitherto attained by any patent, lies in my particular construction wherein those parts which are most susceptible to parting are exposed to view at all times. That is, the ends of the several 45 cables and the connections used in carrying the motion from the reciprocating ram to the hands of the operator, are exposed to view whereby they may be readily inspected and thus accidents will be prevented. Also, I utilize means for transmitting the desired motion which means will not 50 elongate materially under tension. My construction entirely eliminates any levers which might bow and consequently permit improper or slow movement of the guarding means itself.

An understanding of the invention may be had 55 from the following description taken in connection with the accompanying drawings, in which:

Fig. 1 is an elevation showing my invention

applied to a punch press having a substantially vertically movable ram.

Fig. 2 is a similar elevation showing the invention applied to a press in which the ram moves at an incline to the vertical.

Fig. 3 is a plan view of the upper horizontal member of the guard structure of my invention.

Fig. 4 is a fragmentary enlarged elevation of mechanism forming a part of my invention.

Fig. 5 is a fragmentary substantially central vertical section through the construction shown in Fig. 4, and

Fig. 6 is a partial side elevation and section illustrating the grooved wheels on which the hand withdrawing cables are mounted and connected.

Like reference characters refer to like parts in the different figures of the drawings.

The punch press 1 is provided with a table 2 upon which die 3 may be mounted, cooperating with which is a punch 4 secured to the lower end of a reciprocating ram 5, which is reciprocated by the rotation of a crank shaft 6 usually supplied with a fly-wheel 7. The reciprocation of the ram may be by means of a suitable eccentric or other equivalent construction for transmitting rotary motion into reciprocating motion. The construction for reciprocating the ram 5 and the various controls for punch press are old and well known and need not be entered into in detail.

In the guard construction which I have invented, a support is provided including a vertical rod or post 8 having a supporting foot 9. On said rod one end of an upper horizontal beam structure is adjustably mounted. The beam structure comprises, preferably as shown, two spaced apart angle bars 10 connected together and held in spaced apart relation at their end portions by cross bars 11. A sleeve or collar 12 is at one end of the beam structure and is received over the post 8 and may be adjusted to different positions thereon and held by a set screw.

The beam structure, including the spaced bars 10, extends over the upper end of the punch press which, at its upper end, is provided with ears 13 to which a rod or post 14 is pivotally connected at one end, passing upwardly between the bars 10 and having a clamping means 15 thereon to engage with the horizontal legs of the angle bars. It is evident that with either a punch press, such as shown in Fig. 1 in which the ram 5 is vertical, or in one like that shown in Fig. 2 wherein the ram 5 is inclined to the vertical and the other parts of the press adjacent are correspondingly tilted, this supporting structure described may be very readily and easily applied, the clamp 15 being

adjustable to various places in the length of the outwardly extending horizontal legs of the angle bars 10.

A pulley 16 is mounted between said bars 10 adjacent the post 8, a journal bolt passing through the vertical legs of the angle bars. A second pulley 17 is also mounted between said bars 10 on a journal bolt which may pass through any suitable openings of a plurality of spaced apart openings 18 made in the vertical legs of the angle bars 10. The pulley 17 is properly located with reference to the punch press and the large number of openings 18 permit the pulley 17 to be located at the proper position.

15 A pin 19 projects forward from the lower end of the ram 5, moving therewith. An adjustable turn-buckle construction comprising two rods 20 connected by turn-buckle 21 is secured at one end to the pin 19, one end of one of the rods 20 having a pivotal connection thereto. To the opposite end of the opposite rod 20 a cable 22 is connected which passes upwardly over the pulley 17 and thence to the pulley 16 and downwardly substantially parallel to the post 8. The cable 22 is divided between its ends and the adjacent ends are connected by suitable connections such as 23 in Fig. 1 or 23a in Fig. 2. The connection at 23a includes a link which compensates for the greater distance that the pulleys 16 and 17 are spaced apart, this being required by reason of the different angles at which the presses are located. The connection between the pin 19, including the turnbuckle structure and that part of the cable which leads to the pulley 17 should be, as nearly as possible, parallel to the ram 5.

On the post 8 a supporting frame is adjustably mounted. It includes two spaced apart upper and lower brackets 24 with suitable openings through which the post 8 may pass and with set-screws for securing the frame in any position to which adjusted. A rod 25 passes slidably through the members 24 (see Fig. 5). The cable 22 is connected to the upper end of the rod 25. At its lower end it is provided with suitable nuts or a nut and washer against which the lower end of a coiled compression spring 27 bears, the upper end bearing against the lower side of the lower member 24. The rod 25 is formed with a consecutive series of rack teeth 28 at one side as shown.

From the upper and lower members 24 of the frame, bars or brackets 29 extend downwardly and upwardly toward each other, integrally connecting with spaced apart bearings 30 through which a horizontal shaft 31 passes and in which bearings said shaft is rotatably mounted. A pinion 32 is carried on the shaft and is in mesh with rack 28. Suitable collars on the shaft 31, one at each side of the pinion and one at the outer end of each bearing 30, serve to properly locate the shaft and the pinion and hold the parts in desired position.

At each end of the shaft 31 a grooved wheel 33 is mounted. As shown at the right hand end of Fig. 4 and also in Fig. 6, the wheel has a plurality of openings 33a spaced from each other around the center of the wheel. A suitable collar on the shaft has a pin to engage in a selected one of said openings. Each wheel has a large recess or notch 34 in a side thereof. A cable 35 is connected to each of the wheels at the recess by means of a connecting clamp 36. Each wheel has a guard 37 partially around it, 75 which guard is supported by means of bracket

arms, indicated at 38, which are connected to and extend from the ends of the frame previously described. The cables pass from the connecting clamps 36 (Fig. 6) around the wheels and thence through guard sleeves 39, integral with the guards 37 as shown in Fig. 6. Each of the cables at its free end carries a hand engaging member 40, comprising a wristlet to be buckled over the wrist of the operator and a loop through which the thumb may pass. There being 10 two of these members, both hands of the operator are supplied as is evident.

In the operation of the punch press, when the ram is in upper position as shown in Figs. 1 and 2, the spring 27 acts to move the rod 25 to its lowermost position, turning the grooved wheels 33 in a clockwise direction, (Figs. 1 and 2) and releasing the cables 35. This permits the operator sufficient freedom of movement that he can place the work to be fabricated by the 20 press upon the die 3. Then upon the downward reciprocating movement of the ram 5, the cable 22 is pulled over the pulleys 16 and 17, drawing upwardly rod 25, thereby rotating the shaft 31 and rotating the grooved wheels 33 in a 25 counterclockwise direction. This winds the cables 35 upon the wheels 33 and withdraws the hands of the operator from position of danger with respect to the punch. As soon as the punch has performed its operation and has returned to 30 upper position, the cables 35 are released, it being evident that the spring 27 takes up the slack in the cable 22, and rotates the shaft 31 and the parts connected therewith in a direction reverse to the rotation imparted by the downward 35 reciprocating movement of the ram 5.

By placing the pulleys 33 at different positions on the shaft 31, the distance that the operator's hands are pulled away from the punch press is made variable. This is desirable in the case of 40 different sizes of work or in different types of punch presses. The adjustment of the parts 24 of the frame structure described on the post 8 is of value in setting up the guard. Different lengths of links 23a may be used for presses having different degrees of inclination to the vertical. The height of the horizontal beam may be adjusted for different heights of presses. It is evident that the construction is one of substantially 45 universal application to all punch presses and can 50 be readily adjusted to any particular selected press. The construction has proved very practical and useful in actual practice.

The invention is defined in the appended claims and is to be considered comprehensive of all forms 55 of structure coming within their scope.

I claim:

1. In combination with a punch press or the like having a substantially vertical reciprocating ram, of a post located in front of the press, a horizontal beam supported by said post and said press and located above the press, pulleys mounted on the beam, a cable having operative connection at one end to said ram and passing over said pulleys and downwardly adjacent the post, a vertically movable rack mounted on the post, the other end of the cable being connected to the said rack, a shaft mounted on the post, a pinion on said shaft engaging with the rack, a pair of wheels mounted on the shaft and cables connected at one end to said wheels, said cables at their opposite ends having means to connect with the hands of the press operator whereby on downward movement of the ram, the hands of the operator are withdrawn from the press. 75

2. A construction containing the elements in combination defined in claim 1, combined with a spring means operatively connected and associated with said rack to normally move the rack 5 in a direction opposite to the movement imparted thereto by the downward movement of said ram.

3. In combination with a punch press or the like having a reciprocating ram, a post mounted in front of the press, a rack slidably mounted on the post, means cooperatively associated with the rack and ram whereby downward movement of the ram causes upward movement of the rack, a horizontal shaft mounted on the post, a pinion on the shaft engaging the rack, a grooved wheel near 10 each end of the shaft, a collar fixed on the shaft for each wheel, means for adjustably connecting the wheels to their respective collars, said wheels each having a recess at one side, a cable connected to each wheel in said recess and fitting into the groove thereof, each of said cables at its outer 15 end having means to connect with the hands of the press operator, as and for the purposes described.

4. A construction containing the elements in combination defined in claim 3, combined with a coiled compression spring on said rack for pulling the same downwardly as the ram travels upwardly.

5. In combination with a punch press or the like having a substantially vertical reciprocating ram, of a post located in front of the press, a

vertically movable rack mounted on the post, means cooperatively associated with the rack and ram whereby downward movement of the ram causes upward movement of the rack, a shaft mounted on the post, a pinion on said shaft engaging with the rack, a pair of wheels mounted on the shaft and cables connected at one end to said wheels, said cables at their opposite ends having means to connect with the hands of the press operator whereby on downward movement 10 of the ram, the hands of the operator are withdrawn from the press.

6. In combination with a punch press or the like having a reciprocating ram, of a post located in front of the press, vertically movable means 15 mounted on the post, means cooperatively associated with the vertically movable means and the ram whereby downward movement of the ram causes upward movement of the vertically movable means, said operating means including an 20 element extending upwardly alongside of the post in spaced relationship thereto, a pair of cables, each cable having means to connect with the hands of the press operator, means attached to the cables for varying their respective lengths, 25 and connecting means located between the last mentioned means and the vertically movable means whereby movement of the latter operates the former.

EMIL O. GAUL. 30
